SPOUT FOR A WATER RESERVOIR TYPE COFFEEMAKER OR SIMILAR ARTICLE

Max C. Hauenstein, Monroe, Conn., assignor to
General Electric Company

Filed Feb. 27, 1974, Ser. No. 446,519

Term of patent 14 years

Int. Cl. D7—02

U.S. Cl. D7—129

Fig. 1.

Fig. 2.

Fig. 3.

FIG. 4.

FIG. 5.

FIG. 6.

FIG. 1 is a side perspective view of a spout for a water reservoir type coffeemaker embodying my new design;

FIG. 2 is a top plan view thereof;

FIG. 3 is a side elevational view thereof;

FIG. 4 is a bottom plan view thereof;

FIG. 5 is a front elevational view thereof, and

FIG. 6 is a rear elevational view thereof.

I claim:

The ornamental design for a spout for a water reservoir type coffeemaker or similar article, as shown.
